UNITED STATES PATENT OFFICE.

GODFRIED LAUBE, OF HURON, DAKOTA TERRITORY, ASSIGNOR OF ONE-HALF TO T. J. McBRIDE, OF WINNIPEG, CANADA.

STRAW OR HAY BURNING FURNACE.

SPECIFICATION forming part of Letters Patent No. 392,812, dated November 13, 1888.

Application filed January 30, 1888. Serial No. 262,341. (No model.)

To all whom it may concern:

Be it known that I, GODFRIED LAUBE, a citizen of the United States, and a resident of Huron, in the county of Beadle and Territory 5 of Dakota, have invented certain new and useful Improvements in Straw or Hay Burning Furnaces; and I do hereby declare that the following is a full, clear, and exact description of the invention, which will enable others 10 skilled in the art to which it appertains to make and use the same, reference being had to the accompanying drawings, which form a part of this specification, and in which—

Figure 1 is a perspective view of my improved straw or hay burning furnace. Fig. 2 is a vertical sectional view of the same, and Fig. 3 is a cross-sectional view taken through the center of the partly-cylindrical shell or casing and the magazine.

20 Similar letters of reference denote corresponding parts in all the figures.

My invention has relation to straw or hay burning furnaces; and it consists in the improved construction and combination of parts 25 of the same, as will be hereinafter set forth.

In the accompanying drawings, the letter A indicates the shell or casing, partly cylindrical in form and provided at one edge with a hinged door, which, when closed, forms a cylindrical shell or casing. This shell or casing 30 is supported upon a frame, B, constructed of side pieces, C, and crossed lower pieces, D, the rearwardly-projecting one of which is provided with a stop, E. A crescent-shaped sheet, F, is secured to the upper edge of this partly-cylindrical shell, and has projecting therefrom two or more hot-air-conducting tubes, G, which extend either to rooms above the furnace or to rooms on the same floor as 35 the furnace.

H indicates the smoke-pipe for conducting the products of combustion from the straw-magazine, and is attached to the upper ends of the frame, as more clearly shown in Fig. 1, 40 and has its lower edge struck-up, as shown at J, and is provided at its intermediate forward portion with a hook, J. The top of the fuel-magazine slides vertically upon this pipe and 45 consists of the conical body formed with an annular flange, K, and an apertured downwardly-

projecting edge, L, and provided with handles M, and near its upper portion with a notched plate, N. A collar, O, is secured to the upper inner portion of this cover and prevents the said cover, when sliding upon the pipe, from 55 playing laterally theron, which would cause the cover, when being adjusted, to bind upon the pipe.

T denotes the straw-burning magazine, the peculiar construction of which I make no 60 claim for in this application. This magazine is provided with handles U, doors V and W, respectively, through which the fuel may be lighted and attended to, and with a draft-cup, X, communicating with a perforated draft-tube, Y, in the bottom of the magazine. This magazine is inclosed within the partly-cylindrical shell or casing and is supported upon the cross-pieces of the frame and abuts against the stop E, which prevents the magazine from 65 being placed too far in the rear of the shell or casing.

The operation of my invention is as follows: After the magazine has been filled with fuel (straw or hay) it is placed within the casing, 70 and the cover is lowered to fit with its downwardly-projecting edge therein or is adjusted vertically, as may be desired, by means of the hooks upon the stove-pipe and the notched plate of the cover, so as to regulate the draft 75 by means of the apertures in the downwardly-projecting edge of the cover. The fuel is now lighted through the upper door of the magazine, and the draft-cup in the bottom thereof is regulated by means of a sliding damper, X', 80 (shown only in Fig. 2,) in the same manner as is shown and described in my former application, filed December 27, 1887, Serial No. 259,066, so as to cause the desired draft. The door of the shell or casing is provided with 85 circular apertures Z, which are encircled by annular flanges Z', which impinge upon the magazine and prevent the hot air from escaping through the apertures of the door. Through 90 two of these apertures project one of the handles and the draft-cup of the magazine, while the other apertures permit the doors in the magazine to be opened and the fire attended to. The cold air between the magazine and the casing or shell becomes heated and ascends 95 100

through the conducting hot-air tubes to the rooms desired to be heated.

I would have it understood that I do not claim, broadly, the adjustable cover, the apertures in its downwardly-projecting edge for regulating the draft, nor the means for securing it in an adjusted position; but

What I do claim, and desire to secure by Letters Patent, is—

- 10 1. The combination, with a frame, substantially as herein described, a partly-cylindrical shell or casing, and a smoke-pipe supported by the upper ends of said frame, of a removable magazine and an adjustable top.
- 15 2. The combination, with a frame, substantially as herein described, a stop upon said frame, a partly-cylindrical shell or casing, a crescent-shaped top sheet secured to the upper edge of said shell or casing, hot-air tubes in 20 the said top piece and communicating with the interior of the casing, and a hinged door, of a stove-pipe supported by the upper ends of said frame, and an adjustable cover secured thereon.
- 25 3. The combination, with the frame, substantially as described, of a partly-cylindrical

shell supported thereon, a crescent-shaped top sheet secured to the upper edge of said frame, hot-air-conducting tubes secured in said top piece and communicating with the 30 interior of the shell or casing, and a hinged door secured in one of the side edges of the shell or casing, a removable straw-magazine, a vertically-adjustable top, and a smoke-pipe.

4. The combination of a frame, substantially as described, a smoke-pipe secured to the upper end of the same and provided with a struck-up lower end, and a hook upon said smoke-pipe, with a conical top having handles attached thereto, a notched strip secured to 40 its upper edge, and a collar secured to the interior top portion thereof, whereby the said cover is retained against lateral movement when being adjusted.

In testimony that I claim the foregoing as my 45 own I have hereunto affixed my signature in presence of two witnesses.

GODFRIED LAUBE.
